DESIGN FOR TROUSERS

Eddie Bauer, Seattle, Wash.

Application July 26, 1941, Serial No. 102,498

Term of patent 14 years

To all whom it may concern:

Be it known that I, Eddie Bauer, a citizen of the United States, residing at #3230 Lakewood, in the city of Seattle, county of King, State of Washington, have invented a new, original, and ornamental Design for Trousers, of which the following is a specification, reference being had to the accompanying drawing, forming part thereof.

I claim:

The ornamental design for trousers, as shown.

EDDIE BAUER.
